SOUND RESONATING AND AMPLIFYING DEVICE

Application filed December 1, 1928. Serial No. 323,019.

This invention is a sound resonating and amplifying fixture.

One of the important features of the invention is that the surface of a body of liquid is utilized in spreading, amplifying and directing the sound. The body of liquid is in an open topped container with walls which slope inwardly and downwardly; the angle at which these walls are placed have a very material effect on the extent, manner and spreading of the sound waves. The sound waves are directed directly on to the surface of the liquid and instead of being reflected therefrom, apparently roll along the surface of the liquid and then are deflected upwardly by the sloping walls of the container and thereafter spread in all directions.

The sound waves are directed on to the surface of the liquid preferably from a plurality of resonating pipes which are pointed toward the surface of the liquid. The upper ends of the resonating pipes are supported in and have their upper ends flush with a sounding board. The resonating pipes are of different sizes and lengths so as to amplify notes of different pitch.

The sound waves are generated by an electro-magnetic device of any usual kind, the waves first passing into a smaller amplifying cone supported on a baffle board and thence passing into a directing cone preferably of silk, which guides the sound waves smoothly and without distortion to the sounding board and the resonating pipes, which as has been described, resonate and project them on to the surface of the liquid.

In order to prevent distortion and undue vibration, the group of resonating pipes are surrounded by a curtain of silk or the like.

40. The apparatus, with the exception of the liquid container, may be housed in a housing made of wall board or gypsum board or material of like nature.

The described apparatus is particularly adapted for use in auditoriums and halls where much resonance and amplification is necessary. This apparatus gives the desired resonance and amplification without distortion of the sound waves.

50. With auditoriums and halls of different

sizes and heights, a sound resonator and amplifier of different characteristics are needed. This invention provides a resonator and amplifier which can be adjusted to spread the sound waves different ways, according to 55 the characteristics of the auditorium in which the device is used. This adjustment is obtained by varying the angle at which the side walls of the liquid container are placed.

While the inventive concept, as above outlined, may be carried out in a number of different ways, a preferred embodiment is shown in the accompanying drawings. It should be understood that the structure of the drawings is illustrative of one way in 65 which the invention can be carried out.

In these drawings:

Fig. 1 is a side view on a small scale of the sound resonating and amplifying fixture.

Fig. 2 is a section on a larger scale taken 70 on the line 2—2 of Fig. 1.

Figs. 3 and 4 are sections, somewhat enlarged, taken on the lines 3—3 and 4—4 of Fig. 2.

Fig. 5 is a detail of one of the resonating 75 pipes.

Fig. 6 is a section on the line 6—6 of Fig. 2, and

Fig. 7 is a section on the line 7—7 of Fig. 2.

Referring now to these drawings, in which 80 similar reference characters indicate similar parts, the device comprises a plurality of supporting pipes or standards 5, a top member 6 and side walls 7. The top wall 6 is supported by angle irons 6'; the side walls 7 85 fit in between the jaws 8 of bifurcated members 9, secured at suitable points to the supporting pipes 5. The wall elements 6 and 7 are preferably made out of material such as wall board or gypsum board, of the type 90 that is commonly known as "beaver board".

Supported on angle irons 10, is a baffle board 11 having a central opening 12. Co-operating with this opening 12 is an electro-magnetic sound generating device 13, the details of which are not involved in this invention. This sound generating device has a sound amplifying cone 14 secured to the baffle board over the opening 12. Connected to the lower side of the opening 12 is a cone 100

15 of some such material as silk which is designed to guide and confine the sound waves and direct them on to the upper surface of a laminated sounding board 16, made preferably of wood. The sounding board 16 is supported on angle irons carried by the frame members 5. Mounted in the sounding board is a plurality of vertical resonating pipes 17, the upper ends of which are substantially flush with the top of the sounding board. The pipes are secured to pins 18 which pass into small blocks 19 which are set into suitable recesses shown in the sounding board. The pipes 17 have different sound resonating characteristics so that different pipes will respond to and resonate notes of different pitch. The pipes should have a vibration rate extending over at least one octave.

20 Referring to Fig. 2, it will be seen that the side walls 7 extend from the top of the apparatus substantially down to the lower ends of the resonating pipes.

25 In order to obtain resonance of the sound waves without distortion, there is a curtain of silk or the like 20, surrounding the resonating pipes, the upper end of the silken curtain being attached to the sounding board, while the lower end is substantially flush with the lower end of the side walls.

30 The sound waves pass vertically downwardly out of the resonating pipes and are projected directly on to the surface of a body of liquid 21 which is in a container 22, supported on the lower ends of the pipes 5 by a 35 detachable threaded connection, such as the plug 23, so that different types of liquid containers may be mounted at the lower ends of the supporting standards. The liquid container has walls 24 which slope inwardly and downwardly. These walls may be variably 40 positioned with respect to the vertical and to this end the bottom of the container is provided with a plurality of positioning lugs 25. In order to vary the angle of these walls, the walls are simply placed in front of the appropriate lug 25.

45 In operation the sound waves coming out of the small cone 14 are directed smoothly and guided by the silken cone 15 to the sounding board 16, thence passing through the resonating pipes and being projected on to the surface of the liquid. The side walls 7 of gypsum board and the silken curtain 20 prevent the vibration of the frame work of the device. The sound waves hit the surface of the water and instead of being reflected, apparently roll along the surface of the water and are then deflected by the sloping walls 50 24 upwardly and outwardly in all directions. The extent and the manner of the amplification and spreading of the waves is influenced very considerably by the angle at which the side walls are placed.

55 65 The liquid used may be water and it may

be covered with a film of glycerine or oil to prevent evaporation.

Wall board or gypsum board or material of like characteristics is used for the housing elements 6 and 7 because it has sound insulating properties and so does not respond to vibrations.

It should be understood that the invention is not limited to the described details but that it may be carried out in other ways as defined within the scope of the claims.

I claim as my invention:

1. A sound amplifying device comprising in combination a relatively shallow container for a liquid, having a side wall sloping inwardly and downwardly, independently mounted sound generating means for directing sound waves downwardly therefrom onto the surface of the liquid, whereby the sound waves move along the surface of the liquid and then over the sides of the liquid container.

2. A sound amplifying device comprising in combination a relatively shallow container for a liquid, having side walls sloping inwardly and downwardly, means for variably positioning said side walls, and sound generating means for directing sound waves onto the surface of the liquid, whereby the sound waves move along the surface of the liquid and then over the sides of the liquid container.

3. A sound amplifying device comprising in combination an open-topped container for a liquid, sound generating means mounted above the liquid container, sound amplifying means directly below the sound generating means for directing sound waves from the generating means substantially vertically downwardly onto the surface of the liquid, the sound waves, after striking the liquid surface, rolling over said surface and thence outwardly in all directions.

4. A sound amplifying device comprising in combination an open-topped container for a liquid having side walls which may be positioned at various angles to the vertical, and sound generating means mounted above the liquid container, for directing sound waves downwardly onto the surface of the liquid, the sound waves, after striking the liquid surface, rolling over said surface and thence outwardly in all directions.

5. A sound resonating device comprising in combination an open-topped container for a liquid, resonating pipes above the liquid container, and sound generating means above the resonating pipes, the sound waves from the sound generating means first passing through the resonating pipes and then being projected by them onto the surface of the liquid.

6. A sound resonating device comprising in combination an open-topped container for a liquid, the container having side walls

- which slope downwardly and inwardly, resonating pipes above the liquid container, and sound generating means above the resonating pipes, the sound waves from the sound generating means first passing through the resonating pipes and then being projected by them onto the surface of the liquid.
7. A sound resonating device comprising in combination an open-topped container for a liquid, resonating pipes above the liquid container, a sounding board for supporting the resonating pipes, and sound generating means above the resonating pipes, the sound waves from the sound generating means first passing through the resonating pipes and then being projected by them onto the surface of the liquid.
8. A sound resonating device comprising in combination an open-topped container for a liquid, resonating pipes above the liquid container, sound generating means above the resonating pipes, and casing means having the characteristics of wall-board surrounding certain of said parts, the sound waves from the sound generating means first passing through the resonating pipes and then being projected by them onto the surface of the liquid.
9. A sound resonating device comprising in combination an open-topped container for a liquid, the container having side walls which slope downwardly and inwardly, resonating pipes above the liquid container, a sounding board for supporting the resonating pipes, sound generating means above the resonating pipes, and casing means having the characteristics of wall-board surrounding certain of said parts, the sound waves from the sound generating means first passing through the resonating pipes and then being projected by them onto the surface of the liquid.
10. A sound resonating device comprising in combination an open-topped container for a liquid, resonating pipes above the liquid container, the pipes being of different pitch and directed directly toward the open-topped container, and sound generating means above the resonating pipes, the sound waves from the sound generating means first passing through the resonating pipes and then being projected by them onto the surface of the liquid.
11. A sound resonating device comprising in combination an open-topped container for a liquid, resonating pipes above the liquid container, a screen having the characteristics of silk, extending around the resonating pipes, and sound generating means above the resonating pipes, the sound waves from the sound generating means first passing through the resonating pipes and then being projected by them onto the surface of the liquid.
12. A sound resonating device comprising in combination an open-topped container for a liquid, resonating pipes above the liquid container, sound generating means above the resonating pipes, and a substantially cone-shaped member arranged between the sound generating means and the upper ends of the resonating pipes, the sound waves from the sound generating means first passing through the resonating pipes and then being projected by them onto the surface of the liquid.
13. A sound resonating device comprising in combination an open-topped container for a liquid, resonating pipes above the liquid container, sound generating means above the resonating pipes, and a substantially cone-shaped member having the characteristics of silk, arranged between the sound generating means and the upper ends of the resonating pipes, the sound waves from the sound generating means first passing through the resonating pipes and then being projected by them onto the surface of the liquid.
14. A sound resonating device comprising in combination a sounding board, a plurality of resonating pipes passing through the board and supported by it, and sound generating means positioned a substantial distance away from the resonating pipes and substantially in line therewith for directing sound waves directly into said pipes.
15. A sound resonating device comprising in combination a laminated sounding board, a plurality of resonating pipes having their ends passing through the sounding board and terminating substantially coextensive therewith, and sound generating means located a substantial distance above the sounding board and substantially in line with the pipes for directing sound waves directly into the sounding-board-ends of the pipes.
16. A sound resonating device comprising in combination a sounding board, a plurality of resonating pipes of different pitch passing through the board and supported by it, and sound generating means positioned a substantial distance directly above and in line with the pipes for directing sound waves directly into the upper ends of said pipes.
17. A sound resonating device comprising in combination a laminated sounding board, a plurality of selective resonating pipes differing in pitch, having their ends passing through the sounding board and terminating substantially coextensive therewith, and sound generating means positioned directly above said pipes and substantially in line therewith for directing sound waves directly into the sounding-board-ends of the pipes.
18. A sound resonating device comprising in combination a laminated sounding board, a plurality of resonating pipes having their ends passing through the sounding board and terminating substantially coextensive therewith, sound generating means for directing sound waves into the sounding-board-ends of the pipes, and a substantially cone-shaped

member for carrying the sound waves from the sound generating means to said pipes.

19. A sound resonating device comprising in combination a laminated sounding board, 5 a plurality of resonating pipes having their ends passing through the sounding board and terminating substantially coextensive therewith, sound generating means for directing sound waves into the sounding-board-ends of 10 the pipes, and a casing having the characteristics of wall-board surrounding said parts.

20. A sound resonating device comprising in combination a sounding board, a plurality of resonating pipes passing through the 15 board and supported by it, sound generating means positioned a substantial distance directly above the sounding board and substantially in line with the pipes for directing sound waves downwardly directly into said 20 resonating pipes, and a screen, having the characteristics of silk, surrounding the resonating pipes.

21. A sound resonating device comprising in combination a plurality of supporting 25 standards, an open-topped liquid container carried at the lower ends of the standards, resonating pipes supported by the standards above the liquid container, and sound generating means above the upper ends of the 30 resonating pipes.

22. A sound resonating device comprising in combination a plurality of supporting standards, an open-topped liquid container carried at the lower ends of the standards, 35 resonating pipes supported by the standards above the liquid container, sound generating means above the upper ends of the resonating pipes, and housing elements having the characteristics of wall-board, carried by the 40 standards, and forming a housing around certain of said parts.

23. A sound resonating device comprising in combination a plurality of supporting standards, an open-topped liquid container carried at the lower ends of the standards, 45 resonating pipes, a sounding board in which the resonating pipes are mounted, supported by the standards above the liquid container, and sound generating means above the upper 50 ends of the resonating pipes.

24. A sound amplifying device comprising in combination a baffle board, a sound generator comprising an amplifying cone, the cone being secured to the baffle board, and an 55 amplifying cone on the other side of the baffle board, in registry with the first cone.

25. A sound amplifying device comprising in combination a baffle board, a sound generator comprising an amplifying cone, 60 the cone being secured to the baffle board, and an amplifying cone having the characteristics of silk, on the other side of the baffle board, in registry with the first cone.

26. A sound resonating device comprising 65 in combination a casing, pipe carrying means

suspended within the casing, a plurality of open-ended resonating pipes carried by the pipe carrying means, and sound reproducing means above the pipes for directing sound waves downwardly into the open ends of the pipes.

70 27. A sound resonating device comprising in combination a casing, pipe carrying means suspended within the casing, a plurality of open-ended resonating pipes carried by the pipe carrying means, sound reproducing means above the pipes for directing sound waves downwardly into the open ends of the pipes, and means positioned below the lower ends of the pipes for spreading the downwardly-travelling sound waves emanating from the lower ends of the pipes.

75 28. A sound resonating device comprising in combination a casing, pipe carrying means suspended within the casing, a plurality of open-ended resonating pipes carried by the pipe carrying means, sound reproducing means above the pipes for directing sound waves downwardly into the open ends of the pipes, and an open-topped liquid container positioned below the lower ends of the pipes for spreading the sound waves projected thereon from the pipes.

80 29. A sound resonating device comprising in combination a casing; a baffle board and pipe carrying means positioned within the casing; open-ended pipes carried by the pipe carrying means; and sound generating means carried by the baffle board, for projecting sound waves into the open ends of the pipes.

85 30. A sound resonating device comprising in combination a casing; a baffle board and pipe carrying means positioned within the casing; open-ended pipes carried by the pipe carrying means; sound generating means carried by the baffle board, for projecting sound waves into the open ends of the pipes, and means positioned below the lower end of the pipes for spreading the sound waves emanating from the lower ends of the pipes.

90 31. A sound resonating device comprising in combination a casing; a baffle board and pipe carrying means positioned within the casing; open-ended pipes carried by the pipe carrying means; sound generating means carried by the baffle board, for projecting sound waves into the open ends of the pipes, and an open-topped liquid container positioned below the lower ends of the pipes for spreading the sound waves projected thereon from the pipes.

100 In testimony whereof I affix my signature.
CHRISTIAN A. VOLF, JR.
